(57) **CLAIM**

The ornamental design for a bottle mount, as shown and described.

DESCRIPTION

FIG. 1 is a front view of the bottle mount;

FIG. 2 is a side view of the bottle mount of FIG. 1, the other side being a mirror image therof;

FIG. 3 is a rear view of the bottle mount of FIG. 1;

FIG. 4 is a top view of the bottle mount of FIG. 1;

FIG. 5 is a bottom view of the bottle mount of FIG. 1; and,
FIG. 6 is an exploded perspective view of the bottle mount of
FIG. 1.

The broken lines illustrate portions of the bottle mount that
form no part of the claimed design.

1 Claim, 4 Drawing Sheets
